UNITED STATES PATENT OFFICE

GEORGE R. LAMADE, OF WILLIAMSPORT, PENNSYLVANIA

DESIGN FOR A SHADOWGRAPHIC TOKEN

Application filed March 25, 1930. Serial No. 35,023. Term of patent 7 years.

To all whom it may concern:

Be it known that I, GEORGE R. LAMADE, a citizen of the United States, residing at Williamsport, in the county of Lycoming and State of Pennsylvania, have invented a new, original, and ornamental Design for Shadowgraphic Token, of which the following is a specification, reference being had to the accompanying drawing, forming part thereof.

Figure 1 is a view in plan of the shadowgraphic token showing my design.

Figure 2 is a longitudinal sectional view taken on the line 2—2 of Figure 1.

Figure 3 is a view in perspective of the shadowgraphic token embodying the present invention.

I claim:

The ornamental design for a shadowgraphic token, as shown.

GEORGE R. LAMADE.
